UNITED STATES PATENT OFFICE

2,227,789

ROTARY TIN PLATE SHEARS

Walter W. Macfarren, Los Angeles, Calif.

Application June 2, 1936, Serial No. 83,174

15 Claims. (C1. 164-68)

My invention relates to rotary shears, and may be used for the automatic shearing of any material in the form of thin sheets, webs, or strips, as for instance, paper, card board, brass, aluminum, 5 or steel. The present invention is specifically designed for the shearing of rolled steel tin plate stock, or tin plate, from coils.

The machine is designed to shear strip steel from 12" to 32" in width, and of gauges from 10 .007" to .015", and to cut therefrom sections of any fractional lengths between the limits of 12" and 48", and varying by as little as .005".

The speed of operation may be varied from 100 ft. per minute (feed) or less, to 2000 ft. per minute, or more, depending on the length of the 15 cut sections, as will hereinafter appear.

In previously issued patents for rotary flying shears, I have shown machines designed to operate with the peripheral speed of the knives substantially equal to the linear speed of the strip being cut. This is synchronous operation.

In Patent No. 1,994,107, I have shown special electrical and mechanical controls for synchronizing the above named speeds. In various other 25 co-pending applications, particularly Ser. No. 73,790 and Ser. No. 96,501 I have shown rotary shears using various degrees of asynchronism, or unequal speeds between the knives and the strip, to a limited degree.

In the present invention, due to the thin material to be operated on, and its light weight and flexibility, I make use of this asynchronous method to a considerable degree. The present invention also makes use of a "loop" between the primary and the secondary feeding means, in a manner similar to my co-pending application Ser. No. 96,501, except that here the primary feeding means is a leveller. The present invention also makes use of pinch rolls of varying radius for 35 varying the feed of the material, in a manner similar to those shown in my co-pending application Ser. No. 96,501.

The present invention also makes use of multiple shear knives as shown in my co-pending application Ser. No. 73,790 but in this case the knives are all rigidly mounted on the shear drums, and used in a novel manner to cut sections of different lengths as will appear later. In 45 the drawings,

Fig. 1 is an end elevation of the shear proper. Fig. 2 is a plan view of the same partly in section, and with the upper portion omitted.

Fig. 3 is an elevation, partly in section, of the receiving side of the machine.

Fig. 4 is a diagram showing the coil, the lev-

eller, the loop, the pinch rolls, the shear drums, and the receiving and discharge conveyors.

Fig. 5 is an enlarged vertical section through the pinch rolls and the knife drums.

Fig. 6 is a diagram of the drive for the discharge rollers.

Fig. 7 is an end view of a special knife gauge, and

Fig. 8 is a table or data sheet, showing the various cuts, speeds, feeds, gears, et cetera.

For a preliminary general survey, referring to Fig. 4, the strip 2 is drawn from the coil 1 by the leveller 3, which may be of any usual construction, and which should be driven by its own variable speed motor. The guides or chutes 4 extend in a reversed curve from the last leveller roll to the lower end of a belt conveyor 5, comprising the upper pulley 6, the lower pulley 7, the intermediate idler pulleys 8, and the belt 9.

The pinch rolls 10 are adjacent to the pulley 6, and the shear drums 15 and 20 carry the cutting knives 40. The cut sections are discharged by the knives onto the small rollers 21, and from thence pass on to a conveying belt 25. The belt conveyor 5 is preferably driven from the leveller 3, and the operation will be described in more detail later.

The base of the machine is a bed plate 18, upon which are mounted two housings 30 and 35, which are secured to the bed plate 18 by foot bolts 19.

Each of the housings 30 and 35 is provided with accurately aligned upper and lower bores 22, in which are mounted the main roller bearings 23 for the knife drums 15 and 20.

The housings 30 and 35 are of the general form of an elongated O and have no bearing boxes, the bearings 23 being rigidly mounted directly in the bores 22. This construction is rigid, economical, and accurate.

The knife drums 15 and 20 may be duplicates except as to length and are preferably made of forged steel with integral trunnions, and accurately machined all over. Both drums 15 and 20 are provided with extensions 26 to carry the connecting gears 27, which may have straight spur teeth as shown, or may be of the construction shown in my co-pending application Ser. No. 73,790 with double helical teeth and special means for eliminating backlash.

The gears 27 are each keyed to their drums, and clamped by a nut 28 against a spacer 29, as shown. Outside the nut 28 on the upper drum 15, there is mounted a pulley fly wheel 31 to be driven by a belt.

For the specific design of machine illustrated

in the table Fig. 8, two pairs of cutting knives are used, both pairs being used when cutting sections from 12" to 24" long, and only one pair being used when cutting sections from 24" to 48" long.

5 It is obvious however, that for a larger machine, or even for the design shown, four pairs of knives might be used to advantage, and in Fig. 5 I have so shown it. For the present machine, the use of four pairs of knives would enable the machine to cut sections synchronously down to 9" long, and asynchronously down to 6" long.

10 For a machine of say twice the size, and having four pairs of knives, sections could be cut from one foot to eight feet long, using the principles of action herein described. In Fig. 5 the diameter of the knives from tip to tip is 11½" (the gears 27 having the same pitch diameter). The knife periphery is therefore 36.14", but in the table 15 Fig. 8 I have used an even three feet.

15 Each knife 40 is mounted in a milled slot 32, these various slots being exactly parallel to the drum axis both radially and longitudinally. The knives 40 are made of hardened steel and ground 20 on both sides 33 and 34, and on both edges 36 and 37 (Fig. 7).

25 The edges 36 and 37 are oppositely beveled as shown, an amount sufficient to keep them within the circle described by their cutting edges 30 (or corners). The slots 32 are slightly wider than the knives 40, so the latter will enter easily. The cutting side 33 of the knives 40 is always set against the working side 38 of the slots 32, so that if the slots are accurately formed, as they 35 must be, the cutting edge of each knife is exactly registered with the axis of its drum.

30 The knives 40 are held in the slots 32 by a line of hollow set screws 41, there being 12 of these for each knife as shown in Fig. 2. These set 40 screws remain permanently in place, and can be tightened or loosened by a half turn. Clearance spaces 43 are milled for the set screws 41.

45 The bottoms 42 of the slots 32 are bevelled to fit the edges 36 and 37 of the knives 40, and small liners 44 are used to position the knives 50 radially. These liners 44 will vary in thickness to suit the variations in knife width caused by wear and grinding, and in Fig. 7 I have shown a gauge 130 suitable for determining this thickness. This 55 is simply a hardened steel bar having a groove which correctly fits the assembly of knife and liner. Knives and liners thus gauged will fit the drums exactly, without adjustment, and therefore the knives may be quickly changed, or applied.

50 Reverting to Fig. 2, the gears 27 are enclosed by a casing 46 secured to the housing 35. The 60 bearings 23 are held by retainers 47 and 48, and bronze washers 49 are secured to the ends of the drums 15 and 20, and bear against the inner retainers 47. The upper drum 15 is mounted to prevent endwise motion in its bearings, and the lower drum 20 is mounted to permit a slight motion endwise.

65 A variable speed motor 45 is mounted above the machine, and rests on a pair of square tubular members or beams 50, which extend from housing 30 to housing 35 and are secured to both of them. The motor 45 is preferably an exact 70 duplicate of the leveller motor for reasons which will appear later, and has a pulley 51 which drives a belt 52 engaging the pulley 31. A pair of idler pulleys 53 also engage the belt 52, and are mounted on pins 55 supported by a bracket 54, which 75 in turn is secured to the beams 50.

It is to be noted that in operation, the motor 45 is set by usual controls for a desired speed, and that the knife drums 15 and 20 rotate at a substantially constant speed at all times when cuts are being made.

5 The pinch rolls 10 each comprise a tubular shaft 56, a drive member 57 for the same, two end collars 58, three intermediate spacers 59, and four or more pneumatic rubber tires 61. The tires 61 are of the "doughnut" variety, as made 10 for airplanes and small cars, and a size close to the size given herein is commercially available. The shafts 56 are mounted in ball or roller bearings 62, which are held in sliding boxes 63, which latter are adjustable vertically in guides 64 15 formed in the housings 30 and 35.

The boxes 63 are adjusted toward or away from each other by four screws 65 and 66, in such a manner that the surfaces of the tires 61 which contact the strip 2 are maintained at a constant 20 level with reference to the knife drums 15 and 20. In other words the delivery of the strip from the pinch rolls is at a constant level.

There are two sliding boxes 63 for each housing 30 and 35, one for the lower and one for the 25 upper pinch roll 10. Each box 63 has two threaded openings or integral nuts through which the screws 65 and 66 pass, and for each box 63 these threads are right and left hand. For the upper box 63 of housing 30 (Fig. 2) the near threads 30 are R. H. and the far threads L. H. For the lower box the near threads are L. H. and the far threads R. H. The screws 65 and 66 are threaded to correspond.

A pair of brackets 67 connected by ribs 68 are 35 secured to one of the beams 50, and beneath each bracket 67 there is secured a bearing box 72 containing two helical gears 69 and a worm 71. One of the gears 69 is mounted on each of the upper ends of the screws 65 or 66, and the 40 worm 71 engages both gears 69 and is mounted on a shaft 73 supported in bearings 74 in the boxes 72. Each gear 69 is held by a nut 76 so that the weight of the pinch rolls 10, and the sliding boxes 63, is hung on the screws 65 and 66. The 45 worm 71 and the gears 69 may be R. H. or L. H., as convenient.

The left end of the shaft 73 is supported in a bearing bracket 77 mounted on the upper section of the gear box 60, and an indicator 78 is 50 provided, to register with graduations on the face of the hand wheel 75. By the above described mechanism, the pinch rolls 10 are moved toward or away from each other in such a way as to change their working radii R in Fig. 5. 55

This action results in more or less of the strip 2 being fed to the knives 40, as will be readily understood. Applicant believes that the feeding action will be directly proportional to the radius R of Fig. 5, as shown in the table Fig. 8; but in 60 case this is not strictly true, and a modifying factor is present, its value may be readily determined with a pair of tires 61 mounted on adjustable centers, before a machine is built, and the proper allowance made.

65 Referring to Figs. 2 and 3, the gear box 60 may be formed in two or more sections and secured to the housing 30. The gear box 60 contains three shafts 80, 81, and 82 on the level of the axis of the upper drum 15, and a fourth shaft 83 70 directly below the shaft 82. The right end of shaft 80 is inserted in a counterbore 84 in the left trunnion of drum 15, and keyed thereto. Its left end is supported by a bearing 85. The shaft 81 is supported in bearings 86. The shaft 75

82 is tubular and is mounted in bearings 87. The shaft 83 is also tubular and is mounted in bearings 88.

The pinch rolls 10 are driven from shafts 82 and 83 by spindles 90. Each spindle 90 has a small integral spur gear 79 at each end.

The right end of each spindle 90 engages a driving member 57 in one of the tubular shafts 56, the said member 57 being provided with internal gear teeth loosely engaging the teeth of the gear 79 on the spindle 90. The member 57 is keyed or otherwise secured to the shaft 56 to drive it. A similar drive member 89 is loosely set in the left end of each shaft 82 and 83, and these members 89 have a square end 91 which may engage a square hole 92 in a plate 93, secured by bolts 94 to a flange 95 on each shaft 82 and 83.

By this arrangement, the spindles 90 are of ample length to give the required vertical adjustments of the pinch rolls 10, and are concealed and out of the way.

The shaft 80 carries four spur gears A, C, E, and G, all loosely mounted on the shaft, and driven by jaw clutches 96 and 97, which latter are keyed 25 to shaft 80 and are shifted by shifters (not shown) on the vertical shafts 101 and 102, which are in turn operated respectively by levers 105 and 106. (Fig. 3.)

Similar clutches 98 and 99, are mounted on 30 the hollow shaft 82, and operated from similar vertical shafts 103 and 104.

The shaft 81 carries seven spur gears B—M—D—K—F—I—H, all keyed to the shaft. The shaft 82 carries four spur gears N—L—J—100. The shaft 83 carries a gear 110 of equal size to the gear 100, and which meshes with, and is driven thereby, so that the two shafts 82 and 83 always rotate at the same speed, and in opposite directions to drive the pinch rolls 10.

40 These gears have the following dimensions:

Gear symbol	No. teeth	Diam. pitch	Pitch diam.	R. P. M. Speeds
<i>Inches</i>				
45 A	80	8	10	100.00
B	60	8	7 $\frac{1}{2}$	133.33
C	53	6	9 $\frac{1}{2}$	100.00
D	47	6	7 $\frac{1}{2}$	123.40
E	57	6	9 $\frac{1}{2}$	100.00
F	48	6	8	118.75
G	54	6	9	100.00
H	51	6	8 $\frac{1}{2}$	110.00
I	53	8	6 $\frac{1}{2}$	
J	87	8	10 $\frac{1}{2}$	81.22—75.17—72.20—67.01
K	61	8	7 $\frac{1}{2}$	
L	79	8	9 $\frac{1}{2}$	102.95—95.27—91.70—84.94
M	70	8	8 $\frac{1}{2}$	
N	70	8	8 $\frac{1}{2}$	133.33—123.40—118.75—110.00
55 100	66	6	11	
110	66	6	11	

With the shear drums 15 and 20 assumed to run at 100 R. P. M. the gears A—C—E and G will have the same speed, and the shaft 81 will run at 133.33—123.40—118.75— or 110 R. P. M., depending on which gear is driving. The above four speeds may be transferred directly to the pinch roll drive shafts 82 and 83, by means of the equal gears M and N, and the equal gears 100 and 110.

The four primary speeds above may also be reduced by the gears K and L to 102.95—95.27—91.70 and 84.94 R. P. M. for shafts 82 and 83. And 70 also, these speeds may be reduced by the gears I and J to 81.22—75.17—72.20— and 67.01 R. P. M. As shown there are thus available twelve speeds for the pinch rolls 10, varying by gradual steps from 67.01 to 133.33 R. P. M.

As shown by the table Fig. 8, the differences

in these speeds from step to step are covered by the variations in the working radius R of the pinch rolls 10, so that in effect, any speed may be had between 67.01 and 133.33 R. P. M. Or, in other words, the correct rate of feed for the 5 strip 2 may be obtained to cut sections from 12" to 48" long, as shown by the table.

At the delivery side of the machine I provide a pair of brackets 111 and 112 secured respectively to the housings 30 and 35, and which may be 10 connected by integral ribs 113, as indicated in dotted lines in Fig. 1. The brackets 111 and 112 carry the shaft 114 and its pulley 115. They also carry the small discharge rollers 21, and the driving rollers 116 therefore, and one end of the 15 shaft 120.

The driving rollers 116 are short-about 4" face (see Fig. 2) and are provided with rubber rings or sheaths 117, which bear against the small rollers 21 and drive them. The rollers 116 are 20 in turn driven by a pair of rollers 118 on the shaft 120, the same having rubber sheaths 119, which bear against and drive the covers 117 of rollers 116.

The shaft 120 passes through the housing 30, 25 and carries a small sprocket 121 at its left end (Fig. 2), which may be driven from a sprocket 122, secured to the trunnion of the lower knife drum 20, by a chain (not shown). The ratio of this drive should be such that the rollers 21 30 will rotate at a surface speed of about 325 ft. per minute when the knife drums 15 and 20 rotate at 100 R. P. M., in order to insure a free discharge of the cut sections.

The belt conveyor 25 is similar to the one 35 covered by my co-pending application Ser. No. 96,501 and may be driven from its delivery end, or from a point between its ends by a separate motor.

This conveyor may be operated in three different ways, as follows:

1. At the same speed as the delivery rollers 21, which will deliver the cut sections side by side, without overlap. This is not advised.

2. At a slow uniform speed, say $\frac{1}{4}$ " to $\frac{1}{2}$ " 45 advance for each section cut from the strip, which will deliver the sections overlapping.

3. With alternate stops and starts. During the stops the sections will form a pile, and when a new coil is being set in place (or at other times), 50 the conveyor belt 25 can be advanced enough to leave room for a new pile, or the pile just formed can be moved to a desired point. This is the preferred method.

At 123 in Fig. 3 I have shown an oil pump which may be driven by gears 124 from the shaft 83 to pump oil to a reservoir 125, resting on the beams 50, and from which gravity oil feeds may be led to all points requiring lubrication.

Referring to the table Fig. 8, column 1 shows the lengths of the cut sections by inch steps, col. 2 shows the distance travelled (circumferentially) by the knives during the intervals between cuts, or per cut, col. 3 shows whether one or two pairs of knives are in use, col. 4 shows the asynchronous travel of the strip in inches or the amount the strip travels less (minus), or more (plus), than the knives during the interval between cuts, col. 5 shows the same thing expressed in percentage of the knife travel, col. 6 is the assumed speed of the knife drums upon which the other given speeds are based, col. 7 is the corresponding speed of the knives in feet per minute, col. 8 shows the number of cuts made 75

per minute, at these speeds, col. 9 shows the gears in use to give the pinch rolls the proper speed for the section lengths being cut, col. 10 shows the corresponding R. P. M. of the pinch rolls, col. 11 shows the advance of the strip to the knives in feet per minute, col. 12 shows whether the knives exert a "pull" or a "check" on the passing strip, col. 13 shows the amount of this pull or check in thousandths of an inch, and col. 14 shows the effective diameter of the pinch rolls, or twice the working radius R of Fig. 5. The diameter is used as being easier to visualize.

Especial attention is directed to columns 12, 13, and 14, which show the guiding principles of the present invention. It is obvious that for a heavy rotary shear cutting heavy strip steel at high speeds, the strip speed and the knife speed should be substantially the same at the instant of cutting. If this is not so the cutting (feeding) speed must be reduced considerably. Generally speaking, asynchronism is bad. It is also obvious that for thin light sections, some degree of asynchronism may be successfully used, even at high speeds, but the table Fig. 8 is the first time these conditions have been expressed in readily understandable figures, as far as applicant knows.

A machine designer can get more information from this table in a short time than he can obtain from pages of description.

In order to obtain the data in cols. 13 and 14, the following constants for this machine (as previously assumed) are used.

The maximum thickness to be cut is .015" (gauge). Assuming the cut is completed when the knives are at the vertical center line of the drums 15 and 20 as indicated in Fig. 5, the cutting angle, or the angle between the vertical center line and a radius drawn to the point where the knives first grip the strip (when .015" apart) 40 may be computed from the known thickness, and the known knife radius.

For .015" gauge and $5\frac{3}{4}$ " knife radius, the cutting angle is three degrees. The cutting chord, or the distance from the point of knife grip to the vertical center line is .30". The retarding chord (check) is double this, or .60" as the knives must open .015" after the cut is made, to let the strip pass on.

Now it will be evident that with synchronous 50 knife and strip speeds, there will be neither a "pull" nor a "check." Such conditions are shown in the table Fig. 8 for 18" and 36" cut sections. And also, for a minus asynchronism, that is, the strip moving at a lesser speed than the knives, a pull will be produced. The amount of this pull will be the constant cutting chord of .30" multiplied by the percentage of asynchronism. For a 12" cut this is $.30 \times 33\frac{1}{3}\%$ or .10".

Similarly for a plus asynchronism, the amount 60 of the "check" will be the retarding chord of .60" multiplied by the percentage of asynchronism. For a 48" cut this is $.60 \times 33\frac{1}{3}\%$ or .20".

From this it will be seen that the percentage 65 of asynchronism determines the maximum speed at which the shear may be successfully operated, which is just another way of repeating that these speeds should not be too far apart. However, a percentage of asynchronism which would be impossible, or very undesirable on thicker material, 70 may be freely and successfully used on such light material as is now under discussion, because the cutting angle, and the cutting and retarding chords increase rapidly with increase in thickness.

75 Regarding speeds, there is no apparent reason

why a shear of this design, cutting sheet steel of .015" gauge, will not operate smoothly at 2000 feet per minute when making synchronous cuts, as 18" or 36". For a 15" cut the pull is only .05", and for a 21" cut the check is only .10". Similarly, for a 30" cut the pull is only .05", and for a 42" cut the check is only .10".

It is probable then, that sections from 15" to 21" inclusive, and from 30" to 42" inclusive, may be cut almost as fast as for synchronous 10 cuts. It is also probable that the other cuts tabulated which are outside this range, may have to be made at somewhat lower speeds, but for .015" gauge applicant believes a minimum speed of 1000 feet per minute can be successfully used 15 throughout the range of the table Fig. 8, of from 12" to 48".

As shown in Figs. 1, 3, and 5 the path of the strip 2 between the pinch rolls 10 is at a level 20 a little above the path of the strip between the knives 40. This setting is purposely made to constrain the strip 2 to travel in a slight reverse curve or non-rectilinear path between these points. When a "pull" occurs this reverse curve is straightened somewhat, and also the amount 25 of play or torsional looseness between the driving ends of the spindles 90 and the members 57 and 89, is purposely made such that the periphery of the pinch rolls 10 may be freely advanced by the pull on the strip, without affecting any 30 other parts. The amount of this "play" should be at least $\frac{1}{4}$ ".

It is to be noted that the amount of the "pull" given in the table Fig. 8, column 13, will never be fully realized, because the strip will separate 35 when cut about $\frac{2}{3}$ the way through, and this action will be assisted by the pull. While the "check" is double the amount of the "pull" for the same percentage of asynchronism, its effect is practically negligible for thin material, as the 40 strip 2 will merely bend or "bow" a small amount to take up the extra length. This bending action will be assisted and assured by the curved path of the strip between the pinch rolls and the knives, as previously described.

However, for a larger machine of the same 45 type, and one to cut thicker material, I prefer to use a curved guide or guides, as indicated in dotted lines at 126 in Fig. 5. The upper curved surfaces of these guides constrain the strip 2 to 50 take a slight initial bend before the cut occurs; and during the cut, if a "checking" cut, this bend is merely increased to an amount sufficient to absorb the check.

Reverting now to Fig. 4, the operation is as 55 follows, assuming the speeds of the leveller and the shear to have been previously adjusted to a desired relation. The shear runs at as near to a constant (set) speed as its motor 45 will drive it, and the pinch rolls 10 run at an equally constant but different speed determined by the selective gears A—B—C, etc.

The leveller 3 being in motion, the end of a coil of strip 2 is fed to it, and this end passes 60 out and slides down the curved guid 4 until it is engaged by the belt 9, which carries it uphill and between the usual adjustable side guards 127 to the pinch rolls 10.

At this time the roller 11 is depressed and the circuit controlled by it through wires 128 and 70 129 is closed. This circuit leads to the armature of the leveller motor, and includes enough resistance to cut down the set speed of the leveller motor from 3% to 5%.

When the pinch rolls 10 engage the strip 2, it 75

is fed to the knives and cut, and the loop 13 in the strip 2 gradually rises to its lower level 14, and then to its normal or average level 13, and finally to its high position 12, at which point or 5 a little above it, the roller 11 is raised, the aforesaid resistance is cut out, and the leveller motor speeds up to normal speed to drop the loop.

The loop 13 is thus automatically maintained by these slight changes in speed of the leveller 10 motor. In this connection, this loop could be dispensed with by the use of the special synchronizing controls covered by my Patent 1,994,107, but for a small machine I prefer the arrangement herein shown.

15 It will be noted that the power required by the leveller and by the shear is so small and so nearly equal that their motors may be duplicates. It is further evident that the same branch mains could supply both motors. Therefore the variations in line voltage would be the same, and would affect both motors alike, and as the loads on both machines are practically uniform (due to shear fly wheel 31), these two motors could probably be made to run at speeds within 3% of each 25 other, by the usual field resistances.

At the higher operating speeds it might be necessary or desirable to slow down both the leveller and the shear while a new strip was entering the pinch rolls. For this purpose a joint 30 control of the two motors could be used.

It will be understood that very fine adjustments as to the lengths of the cut sections may be obtained by manipulation of the hand wheel 15, which controls the working radii R of the 35 pinch rolls. It is of course evident that any lengths of cut sections between the inch lengths shown in the table Fig. 8 may be obtained in this way, and it will be also evident that if the pinch rolls 10, at the start of a table division, 40 as say 35", are too large to make an intermediate cut, of say 35 $\frac{1}{4}$ ", the next geared speed can be used, as for a 36" cut, and the working diameter of the pinch rolls reduced from 11.13" to the dimension necessary. As previously shown, 45 additional geared speeds may be easily incorporated in the design.

In regard to the durability of the pneumatic tires 61 on the pinch rolls 10, 1000 feet per minute feed of the strip 2 is equal to 11.4 miles 50 per hour. At this speed, and for the light duty required, the tires 61 should give 20,000 miles of service, which is equal to 1754 hours, or 220 55 8-hour days, or about a year's service, as it is not probable the shear could be kept in constant operation at this speed. The foregoing description is believed to fully cover the present invention, and to show that a machine constructed in accordance therewith is comparatively simple, and 60 may be very accurate, reliable, and durable. Where sizes, dimensions, gear ratios, or other similar data are given, it will be understood that such data is assumed, and given for illustrative purposes only, and is subject to wide variation 65 to meet the conditions imposed by any specific design.

I claim as my invention:

1. In a rotary shear for making transverse cuts on moving material in the form of a strip, a pair 70 of equal diameter rotary knife carrying drums mounted on fixed centers and geared together, cutting knives carried thereby, means for feeding the strip to the knives, means to drive the feeding means to feed the strip synchronously to the speed of the knives, and other means to

drive the feeding means asynchronously to the speed of the knives.

2. The combination of a leveller, a rotary shear in tandem relation thereto, and having cutting knives adapted to make transverse cuts on strip 5 material fed to it by the leveller, a pair of variable speed pinch rolls for feeding the material to the cutting knives, and means for forming and maintaining a loop in the material between the leveller and the said pinch rolls, the said 10 loop being automatically controlled by variations in speed of the leveller.

3. In a rotary shear for making transverse cuts on moving material in the form of a strip, 15 a pair of rotary knife carrying drums mounted on fixed centers and geared together, cutting knives carried thereby, a pair of pinch rolls each provided with one or more pneumatic rubber tires for contacting the strip and feeding the same to the knives, and means for varying the working radius of the said pneumatic tires to vary the length of the strip so fed.

4. In a rotary shear for making transverse cuts on moving material in the form of a strip, 25 a pair of rotary knife carrying drums mounted on fixed centers and geared together, cutting knives carried thereby, a pair of pinch rolls each provided with one or more pneumatic rubber tires for contacting the strip and feeding the same to the knives, and means for varying the working radius of the said tires to vary the length of strip so fed, comprising a screw down mechanism which may be operated to bring the pinch rolls closer to, or further from each other.

5. In a rotary shear for making transverse 35 cuts on moving material in the form of a strip, a pair of rotary knife carrying drums mounted on fixed centers and geared together, cutting knives carried thereby, a pair of pinch rolls each provided with one or more pneumatic rubber 40 tires for contacting the strip and feeding the same to the knives, means for varying the working radius of the said tires to vary the length of the strip so fed, in combination with a set of selective gears for varying the speed of the pinch 45 rolls.

6. In a rotary shear for making transverse cuts on moving material in the form of a strip, 50 a pair of rotary knife carrying drums mounted on fixed centers and geared together, cutting knives carried thereby, a pair of pinch rolls for feeding the material to the knives, and a gear box containing four shafts, the first shaft being driven at the same speed as the knife carrying drums, and the second shaft being driven from the first shaft, means for driving the said second shaft at four different speeds, means for driving the third shaft from the second shaft at twelve or more different speeds, and means for driving the pinch rolls directly from the third and fourth shafts respectively, and at each of the above mentioned twelve or more speeds to vary the feed of the strip.

7. In a rotary shear for making transverse cuts on moving material in the form of a strip, 65 a pair of rotary knife carrying drums mounted on fixed centers and geared together, cutting knives carried thereby, a gear box containing selectively operated gears, a pair of final shafts in the said gear box, a pair of pinch rolls for 70 feeding the material to the cutting knives, and a spindle connecting each of the said final shafts with one of the said pinch rolls to permit of bodily adjustment of the latter.

8. In a rotary shear for making transverse cuts

on moving material in the form of a strip, a pair of rotary knife carrying drums mounted on fixed centers and geared together, cutting knives carried thereby, a gear box containing selectively operated gears, a pair of hollow shafts in the said gear box, a pair of pinch rolls for feeding the material to the cutting knives, the said pinch rolls each being mounted on a hollow shaft, and a spindle connecting each of the hollow shafts in the gear box with one of the said hollow pinch roll shafts, the said spindle having most of its length within the said two hollow shafts.

9. In a rotary shear for making transverse cuts on moving material in the form of a strip, a pair of rotary knife carrying drums mounted on fixed centers and geared together, cutting knives carried thereby, a series of small rollers adjacent to the knife drums and below the delivery point of the knives, a shaft driven from one of the said knife drums, and frictional driving connections between the said shaft and the said rollers.

10. The combination with a leveller, of a rotary shear arranged to receive the material as fed to it by the leveller, and cut it transversely into desired length sections, means for starting a loop in the material between the leveller and the shear comprising a descending guide or chute to receive the material from the leveller, an inclined belt conveyor for receiving the front end of the strip from the said chute and carrying it to the shear, and means for automatically maintaining the said loop when formed.

11. In a rotary shear for making transverse cuts on moving material in the form of a strip, a pair of rotary knife carrying drums mounted on fixed centers and geared together, cutting knives carried thereby, a belt conveyor arranged to receive the cut sections as discharged by the cutting knives, and an intermittently operable drive for the said conveyor, whereby the belt may be stopped to allow the cut sections to form a pile thereon, and then started to convey the said pile to a desired point of discharge.

12. In a rotary shear for making transverse cuts on moving material in the form of a strip, a pair of rotary knife carrying drums mounted on fixed centers and geared together, cutting knives carried thereby, a pair of pinch rolls for feeding the strip to the cutting knives, a gear box for driving the pinch rolls at variable speeds to vary the rate of strip feed, an elevated oil reservoir, and an oil pump within the gear box and driven by one of its shafts to keep the said reservoir supplied with oil, from whence it may be fed by gravity to points requiring lubrication.

13. In a rotary shear for making transverse cuts on moving material in the form of a strip, a pair of rotary knife carrying drums mounted on fixed centers and geared together, cutting knives carried thereby, and means for feeding the strip to the cutting knives comprising the combination of pinch rolls, speed varying gears to drive the same, the said pinch rolls having continuous unbroken outer driving surfaces for all adjusted radii, and means for varying the radii of the said pinch rolls by small amounts so as to produce cut sections varying in length by a few thousandths of an inch.

14. The method of operating a rotary shear having a plurality of pairs of rigidly attached co-acting shear knives, consisting in feeding the material to be cut to the knives with a degree of asynchronism proportioned to the number of pairs of knives in use, in order to cut off sections of desired length.

15. The method of operating a rotary shear having two or more co-acting pairs of detachable shear knives, to cut off sections of desired length from a moving strip, comprising the use of a single pair, or a plurality of pairs, of knives, feeding the strip to the knives with a degree of asynchronism to produce the cut lengths desired, and rotating the knives at a speed in proportion to the degree of asynchronism used.

WALTER W. MACFARREN.
